WILLARD E. BUSH, OF DAMASCUS, PENNSYLVANIA.

Letters Patent No. 83,252, dated October 20, 1868.

IMPROVED CAR-COUPLING.

The Schedule referred to in these Letters Patent and making part of the same.

To all whom it may concern:

Be it known that I, WILLARD E. BUSH, of Damascus, in the county of Wayne, and State of Pennsylvania, have invented a new and improved Automatic Car-Coupling; and I do hereby declare that the following is a full, clear, and exact description thereof, which will enable those skilled in the art to make and use the same, reference being had to the accompanying drawings, forming part of this specification.

The invention relates to an improvement in the coupling used for uniting railroad-cars, whereby they are rendered more secure, and less liable to get out of order than those of ordinary construction, the improvements being more particularly designed to apply to a car-coupling for which I now have an application for a patent pending.

And the invention consists in attaching spring-catches to the coupling-pin, to prevent its displacement by the motion of the cars, and in the formation of the ends of the coupling-link, and in the provision made for holding the link in place.

Figure 1 is an outside longitudinal view of a draw-head, showing the link and coupling-pin in place, and the spring-catches attached to the pin.

Figure 2 is a vertical section of fig. 1, showing my improvement.

Similar letters of reference indicate corresponding parts.

A is the draw-head.

B is the coupling-link.

C is the coupling-pin.

To the upper end of the coupling-pin there are attached two springs, *d d*, by rivets or otherwise, as seen at *e*. These springs have shoulders formed on them, marked *f*.

In the pin-hole through the draw-head, there is a recess, *g*, with a projecting lip, *h*, under which lip the shoulders *f* catch, as the pin is inserted.

As the pin is pushed down, the springs are compressed by the hole above the recess or lip *h*, but when the shoulders *f* have passed below the lip, the springs expand, and the shoulders catch under the lip, as seen in fig. 2.

In this position the pin is effectually prevented from jumping out by the motion of the cars, consequently there is no danger of the cars uncoupling when in motion.

J is the spring-bar in the draw-head, against which the coupling-pin impinges when the cars are coupled.

The end of this bar is serrated horizontally, as seen in the drawing, at *i*, and the ends of the link are bevelled off, so as to fit the angular grooves in the end of the bar.

By these grooves and the bevelled ends of the link, and by the pressure of the spring-bar against the end of the link, the link is held in a horizontal position at all times, while it will accommodate itself to any difference in the height of the cars in coupling.

By this arrangement the link cannot drop, but will always be ready for coupling with another car without aid from any attendant.

I do not claim the construction of the draw-head in this application as a novelty.

What I do claim, and desire to secure by Letters Patent, is—

The springs *d d*, with their shoulders, *ff*, and the lip *h*, on the draw-head, substantially as and for the purposes herein shown and described, in combination with a draw-head of a car-coupling.

The above specification of my invention signed by me, this 3d day of May, 1868.

W. E. BUSH.
